(57) **CLAIM**

The ornamental design for a bracket, as shown and described.

DESCRIPTION

FIG. 1 is a top perspective view of a bracket, showing my new design;

FIG. 2 is a front elevation view thereof, the rear elevation view being a mirror image thereof;

FIG. 3 is a left-side elevation view thereof, the right-side elevation view being a mirror image thereof;

FIG. 4 is a top plan view thereof; and,

FIG. 5 is a bottom plan view thereof.

The dash-dash broken lines depict portions of the bracket that form no part of the claimed design.

The dot-dash broken lines define the bounds of the claimed design and form no part thereof.

1 Claim, 2 Drawing Sheets
